UNITED STATES PATENT OFFICE.

ORVILLE A. REITZ, OF ULM, ARKANSAS.

RAILWAY-CROSSING SIGNAL.

Application filed February 3, 1928. Serial No. 251,621.

This invention relates to new and useful improvements in railway crossing signals and aims to provide a crossing signal of the electrical variety that is operated by the passage of a train within a certain area of the trackway at opposite sides of the road crossing so that motorists or pedestrians will be warned of the approach of the train.

One of the most important objects of this invention resides in the provision of such a signal that is extremely simple of construction and that is positive in operation and one that may be installed at very moderate cost.

In the drawings wherein like reference characters indicate corresponding parts throughout the several views:

Figure 1 is a transverse section of a highway at the point of a railroad crossing equipped with my improved signal, this figure also indicating generally the mechanism associated with the train engine for completing an electrical circuit to the indicating means when the train approaches the crossing.

Figure 2 is a longitudinal section through the signal casing that is arranged within the roadway, and that is equipped with an electrical signalling means constructed in accordance with the present invention.

Figure 3 is an enlarged transverse section across the track way and through the signal casing, this view also disclosing fragmentarily the engine in elevation and partially in cross section for bringing out the means operating to complete the circuit between the signal units and a storage battery located in the engineer's cabin when the engine approaches the roadway.

Figure 4 is a diagrammatic view of the electrical circuit of the signal mechanism.

Figure 5 is a plan view of the primary signal unit, the lid of the casing thereof being removed.

Figure 6 is an enlarged fragmentary section through the engineer's cabin of the locomotive that is equipped with means for completing the circuit between the battery and the signal devices when the train approaches the crossing, and

Figure 7 is a perspective of the primary signal unit, the signal member being disclosed as in raised operable position.

Now having particular reference to the drawings A designates a highway across which runs a track way including the usual

spaced rails B-B. In carrying out the present invention there is provided a pair of ramp rails 5-5 of great length that are arranged at the outer sides of the rails B-B and at opposite sides of the roadway A. Depending from the floor of the engineer's cab of the locomotive C is an arm 6 to the lower end of which is pivoted a lever 7, the upper end of which extends through and is movable within a slot c in the floor of the engineer's cabin of the locomotive as clearly indicated in Figure 6.

Arranged within the engineer's cabin adjacent the end of the lever 7 projecting into the cabin is a leaf spring contact member 8 that is adapted to be engaged by the inner end of the lever when the same is swung from the full to the dotted line position indicated in Figure 6. Arranged upon the lower end of this lever 7 is a ramp engaging roller 9 that will engage the adjacent ramp 5 to cause the swinging of the lever from the full to the dotted line position as disclosed in said view. Suitable spring means designated generally 9' is provided so as to return the lever to the circuit breaking full line position after the roller 9 has passed beyond the ramp 5.

Located within the engineer's cabin of the locomotive is a battery or other source of electrical current indicated by the reference character D one terminal of which is connected to the spring contact 8 while the opposite terminal thereof is grounded to the locomotive as disclosed in the diagrammatic view, Figure 4.

Arranged vertically at opposite sides of the roadway A are posts 10-10 supported between which and above the road A is a signal box 11 within which is an electric bulb 12 that is electrically connected to the ramp rails 5-5 and to one of the track rails B as disclosed in Figure 4, with the obvious result that when the train passes into that area of the trackway equipped with the ramp rails 5-5 the circuit will be completed from the battery D to the bulb within the lamp box as is obvious.

Furthermore the invention consists of an additional and what is considered the primary signalling means, the same consisting of an elongated casing 12 having a removable lid 13 that is formed with an elongated slot 14. Pivoted within the casing directly beneath this lid is an elongated bar or flag staff 15, the inner end of which is pivotally

secured to the cores of a pair of solenoids 16—16 arranged within the casing. The forward end of this bar or flag staff is equipped with a rigid material warning flag 5 17 having suitable danger indicating characters thereon.

Said solenoids 16—16 are as disclosed in a diagrammatic view in Figure 4 electrically connected to the adjacent rail B and to the 10 pair of ramp rails 5—5 so that when the lever 7 is swung into engagement with the spring contact 8 the circuit will also be completed to these solenoids for obviously raising the bar or flag staff out of the casing 12 15 to the position disclosed in Figures 2 and 7.

In view of the foregoing description when considered in conjunction with the accompanying drawings it will be apparent that I have provided a highly novel, simple and 20 efficient railway crossing signal device that is well adapted for all the purposes heretofore designated, even though I have herein shown and described the invention as consisting of certain detail structural elements, 25 it is nevertheless to be understood that minor changes may be without departing from the spirit and scope of the appended claim.

Having thus described the invention, what I claim as new and desire to secure by Letters 30 Patent is:—

In a railroad crossing signal of the character described, a pair of current conducting

ramp rails located adjacent the opposite rails of the trackway and at opposite sides of the roadway, a current conducting arm 35 adapted for pivotal attachment to a locomotive adjacent one of the rails of the trackway and arranged to engage a ramp rail, the upper end of the arm movable within the engineer's cabin of the locomotive, and adapted to engage a contact member when said arm is swung by the engagement of the lower end with the ramp rail, and electrical signalling means located adjacent the roadway in circuit with one of the rails and said ramp 40 rails and a source of current carried by the locomotive, said source of current being grounded to the locomotive and electrically connected to said contact whereby the circuit to the signalling means is completed due to the movement of the said arm when engaging said ramp rail, said signalling means consisting of a casing disposed within the surface of the roadway, a pair of solenoids 55 within the casing electrically connected to the ramp rail and one of said trackway rails, a flag staff pivoted adjacent one end within the casing, and having an indicating flag upon its outer end, and a pair of solenoid cores pivoted to the inner end of the flag staff and slidably within said solenoids. 60

In testimony whereof I affix my signature.

ORVILLE A. REITZ.
